[57] CLAIM

The ornamental design for a flower pot cover, as shown and described.

DESCRIPTION

FIG. 1 is a perspective view of a flower pot cover showing my new design;

FIG. 2 is a top plan view thereof;

FIG. 3 is a bottom plan view thereof; and,

FIG. 4 is a side elevational view thereof, all sides being identical.

The horizontal and diagonal cross hatching shown on the inner and outer surfaces, respectively, is intended to be symbolic of contrasting conventional surface effects which extend entirely across each side. The flower pot has no substantial thickness.
